PROCESS FOR MANUFACTURING LUBRICATING OIL

Filed Jan. 22, 1927

Inventor
Edgar M. Clark
By his Attorney *W. M. Straw*

UNITED STATES PATENT OFFICE

EDGAR M. CLARK, OF NEW YORK, N. Y., ASSIGNOR TO STANDARD OIL DEVELOPMENT COMPANY, A CORPORATION OF DELAWARE

PROCESS FOR MANUFACTURING LUBRICATING OIL

Application filed January 22, 1927. Serial No. 162,727.

This invention relates to improvements in the manufacture of lubricating oils. In a preferred embodiment the invention includes heating the lubricating oil to a vaporizing temperature in a pipe still or heating coil, introducing the hot oil into a fractionating tower in which the oil vaporizes, treating the hot lubricating oil condensate formed in the tower, and vacuum-distilling the hot treated oil.

The invention will be fully understood from the following description, read in connection with the accompanying drawing, in which the figure is a diagrammatic perspective view of equipment for practicing the process.

Referring to the drawing, reference numerals 1, 2, 3, and 4 denote a battery of series-connected stills, into the first of which charging stock is passed through a pipe 5. Vapor lines 6 are connected to the stills. A pipe 7 having a valve 8 conveys the residue of lubricating oil in the last still 4 to branch pipes 9 and 10 and pumps 9^a and 10^a, which forward the oil to pipe stills or heating coils 11 and 12. Steam pipes 11' and 12' connect with the coils. From the coils the oil passes through pipes 13 and 14, respectively, into the lower chambers of the fractionating towers 15 and 16. These pipes should be lagged to prevent substantial loss of heat. Vapor lines 19 lead from the tops of the towers and are in circuit with a barometric condenser 17 and vacuum pump 18.

A cooling coil 20 is located in the upper portion of the tower 15. A pan 21 collects condensate, which flows through pipe 22 to a treating tank 23, having a steam vent 23'. A drain pipe 23^a leads from the tank 23 for conducting off excess alkali solution. Bell cap plates 20', or other equipment for fractionation or preventing entrainment, are preferably provided between the inlet to the tower and the pan 21. A bell cap plate 20'' may be placed between the top of the tower and the cooling coil 20. Care should be taken not to impose much resistance to vapor flow anywhere in the tower, since high vacuum is usually desired. A steam pipe 24 leads into the bottom of the

tower 15 and is connected to a spray head 25. A drawoff pipe 26 having a valve 27 is provided at the lower part of the tower. The towers 15 and 16 are equipped in the same way. A branched pressure equalizing line 23'' connects the tank 23 with the upper part of the towers.

From the treating tank 23 the oil passes through pipe 28, valve 29, and branch pipes 30 and 31, respectively, into the stills 32 and 33. These stills have towers 34 and 35 from which vapor lines 36 and 37 lead to a condenser 38. A drum 39 receives liquid from the condenser. Reduced pressure is maintained on the system by a vacuum pump 40. A drawoff line 41 and pump 42 are connected to the drum 39.

Valves 9' and 10' are installed respectively in branch pipes 9 and 10, and valves 19', and 19'' in the pipes 19. Valves 30' and 31' are placed in branch pipes 30 and 31, and valves 36' and 37' in the pipes 36 and 37.

The operation of the improved process in a preferred form is as follows:

A crude oil suitable for the production of lubricants, in this example Colombian crude, is charged into the first still 1 through the pipe 5 and flows through the series of stills. Light naphtha, gasoline, kerosene, and gas oil are taken off successively. The lubricating oil bottoms remaining in the last still 4 will ordinarily be about 45% of the crude charged. These bottoms are passed through pipes 7, 9, and 10 into the heating coils 11 and 12. In these coils the oil is heated to a temperature at which the lubricating constituents tend to vaporize, for example around 800° F. The hot oil is discharged without substantial loss of heat directly into the fractionating towers 15 and 16 through pipes 13 and 14. Steam is preferably injected through pipes 11' and 12' to increase the velocity of flow through the coils.

Both coils and both towers are used in large scale operation, since effective heating and vaporization of the oil is best accomplished in this way. However, either heating coil 11 and tower 15, or heating coil 12 and tower 16, may be used if desired. Valves 9', 10', 19', 100

and 19" will be adjusted to shut off the coil and tower not in use.

Steam may be injected into the bottom of each tower through pipe 24 and spray head 25, to aid in the distillation of the oil. The absolute pressure in the towers corresponds to about 25 mm. of mercury, in the preferred operation, but this pressure may be varied. Under the conditions stated, the lubricating oil constituents entering the towers are vaporized for the most part and pass up through the baffle means 20' into contact with the cooling coils 20. These should be regulated so as to avoid cooling the lubricating oil much below its condensation temperature. The heavy residue is withdrawn from the towers through pipes 26, when required.

Steam and light vapors pass through the pipes 19, substantially all the lubricating oil being condensed in the towers and caught in the pans 21. It is discharged from the pans without substantial heat loss into the treating tank or agitator 23. The temperature of the oil may be about 500° F. when it enters the tank 23. In this it is thoroughly mixed with a treating agent, preferably an alkali solution. Sodium hydroxide solution of about 33° Bé. strength is best for most purposes. The treating should be continued until all the organic acidity of the oil is neutralized. The oil may leave the tank 23 at about 274° F. An important feature of the process is the treatment of the lubricating oil while hot. In this way heat losses are avoided and a better product is obtained. Very heavy lubricating oils can be made with particular advantage according to this method.

The treated oil is passed then through the pipe 28 and branch pipes 30 and 31 into the stills 32 and 33, which are fired moderately, care being taken not to crack the oil. These stills are preferably run without steam and maintained under a suitable high vacuum, for example, an absolute pressure corresponding to about 15 mm. of mercury. Lubricating oil is taken off through the vapor lines 36 and 37, condensed in the coil 38, and collected in the tank 39. Either of the stills 32 and 33 may be used alone, if desired. In such case, valves 30', 31', 36', and 37' will be adjusted to shut off the still not in use. If two different lubricating oil fractions are to be produced, the stills 32 and 33 may be connected in series.

It is feasible to operate the towers 15 and 16 at atmospheric pressure with the supply of large amounts of steam. Reduced pressure operation is preferable. Steam may be used in the final stills 32 and 33 and the pressure reduction correspondingly lessened.

Various changes and alternative arrangements in the described process and apparatus may be made within the scope of the appended claim, in which it is my intention to

claim all novelty inherent in the invention as broadly as the prior art permits.

I claim:

In the manufacture of lubricating oils, the improvement that comprises heating a lubricating oil fraction to a vaporizing temperature, passing the hot oil into a fractionating zone maintained at an absolute pressure corresponding to about 25 mm. of mercury, injecting steam into the lower portion of said zone, condensing lubricating oil constituents vaporized in said zone, withdrawing such constituents, subsequently treating them while hot with an alkaline solution in a separate zone, and distilling the treated oil at an absolute pressure or partial pressure corresponding to about 15 mm. of mercury.

In testimony that I claim the foregoing as my invention, I affix my signature.

EDGAR M. CLARK.
